UNITED STATES PATENT OFFICE.

JOHN ADAMS WILSON, OF MANCHESTER, ENGLAND, ASSIGNOR TO THOMAS HARDY, OF MANCHESTER, ENGLAND.

FILTER-PRESS.

1,316,404.

Specification of Letters Patent. Patented Sept. 16, 1919.

Application filed May 10, 1919. Serial No. 296,114.

To all whom it may concern:

Be it known that I, JOHN ADAMS WILSON, a British subject, of Manchester, county of Lancaster, England, residing at Provost Road, Charlton - cum - Hardy, Manchester, England, have invented certain new and useful Improvements in Filter-Presses, of which the following is a specification.

This invention relates to the plates of filter presses which support the filtering cloth or material in which the plates are constructed or built up of a number of series of bars fitted into a strong frame between which the effluent liquor flows.

The invention consists in the particular construction of each bar of the plate with grooves to face one another at the sides abutting at the center so that when the bars are placed side by side in the frame they form corrugations or indentations on the face of the plate with recesses cut under the face into which the filtering cloth cannot sag however great the pressure applied to the press and so a constant and uninterrupted flow of the effluent liquor is maintained into a channel in the frame.

The invention will be fully described with reference to the accompanying drawings.

Figure 1 is a side elevation (partly in section) of a single plate of a filter press constructed according to the invention.

Fig. 2 is a sectional plan.

Fig. 3 is a vertical section.

Fig. 4 is a vertical section showing modification of frame of plate lined with lead porcelain or other non-corrodible material.

Fig. 5 is a detail view of a single bar.

Each plate of a filter press is constructed with a frame A grooved along the top and bottom, the bottom groove *a* forming a channel into which the effluent water flows from which it is drawn or drains off through a spout or tap *a'*, and a number of bars B which are fitted into the top and bottom grooves of the frame A. The frame A is made with apertures C in the top rail opening into the groove therein and the bars B are inserted therethrough one by one and

passed into position side by side until the plate is complete.

The center of the plate is formed of a narrow corrugated plate D with a central hole *d* through which the liquor flows as it is pumped in.

Each bar B is approximately of the shape shown in Figs. 2 and 5, with two grooves *b* cut under the face at one side and two grooves *b'* cut under the face at the other side. When the bars are in position the center members *b* abut and the grooves *b* *b'* face one another forming recesses under the face of the plate into which the filter cloth while stretched across the face of the plate cannot sag.

The bars B may be made of metal, wood, porcelain, earthenware, or other suitable material and may be strengthened or reinforced by a wire or metal bar through the center.

The apertures C in the top rail of the frame A are closed with pegs *c* of wood or other suitable material.

When the frame A is made of metal such parts of it as come into contact with liquors or acids may be provided with a protective covering or lining of lead, wood, vitreous enamel or other acid resisting material and the bars B may be similarly coated. Steam passages E may be formed in the top and bottom of the frame and these when the plates are bolted together will form continuous passages from end to end of the press.

The bars B form a corrugated plate and the grooves *b* *b'* therein prevent the filter cloth sagging into the grooves and preserve a free channel for the effluent liquor down to the channel *a*.

What I claim as my invention and desire to protect by Letters Patent is:—

1. Bars for building up the plates of filter presses constructed with central abutting members and grooves in the adjacent faces to form channels under the face of the plate for the effluent liquor to flow from top to bottom of the plate substantially as described.

2. In a plate for filter presses the com-

bination with a frame provided with channels top and bottom of a central corrugated plate with an aperture for the flow of the liquid and a plurality of bars inserted there-
5 in, each bar provided with a central abutting member and double grooves facing one an-
other to provide vertical channels through
which the effluent liquor flows.

**Copies of this patent may be obtained for five cents each, by addressing the "Commissioner of Patents,
Washington, D. C."**

In testimony whereof I have hereunto set
my hand in presence of two subscribing wit- 10
nesses, this 15th day of April, 1919.

JOHN ADAMS WILSON.
